UNITED STATES PATENT OFFICE

157,781

DINING BREAKFRONT OR SIMILAR ARTICLE

William C. Pahlmann, New York, N. Y.

Application January 14, 1949, Serial No. 239

Term of patent 3½ years

(Cl. D33—19)

To all whom it may concern:

Be it known that I, William C. Pahlmann, a citizen of the United States, residing at New York, in the county of New York and State of New York, have invented a new, original, and ornamental Design for a Dining Breakfront or Similar Article, of which the following is a specification, reference being had to the accompanying drawing, forming a part thereof.

Figures 1 and 2 are views in perspective respectively showing the dining breakfront in a closed and an opened position embodying my new design.

I claim:

The ornamental design for a dining breakfront or similar article, as shown.

WILLIAM C. PAHLMANN.
